ABSTRACT: This invention relates to an open top multisided baking pan having a bottom and upstanding sidewalls and a flat top flange which flares outward at the open top of the pan, the top flange including straight sections of uniform width and corners therebetween. A rim depends downward from the outer peripheral edge of the top flange. From the bottom of the rim straight sections of a bottom flange extend inward toward the sidewalls, the adjacent ends of such straight sections of the bottom flange being separated from one another at regions beneath the corners of the top flange. Each corner of the top flange is stiffened and reinforced by a zone thereof which extends outward beyond an arc of a circle connecting the outer peripheral edges of adjacent straight sections of the top flange and having the same center of radius of curvature as that of the inner peripheral edge of the corner of the top flange. Also, the ends of adjacent straight sections of the bottom flange are disposed beneath the outward extending zone of each corner of the top flange to further stiffen and reinforce the top flange at each corner. Alternatively, the width of the top flange at the corners is greater than at the straight sections, the radius of curvature of the outer peripheral edge of each corner of the top flange being less than the radius of curvature of its inner peripheral edge.

FIG. 1

FIG. 2

FIG. 3

FIG. 4

BAKING PAN HAVING TOP REINFORCING FLANGES

BACKGROUND OF THE INVENTION

1. Field of the Invention

Baking pans often are subject to considerable expansion due to heating. This sometimes causes the bottom of a pan to curve and often the entire pan becomes distorted. Although a heated pan usually tends to assume its original shape when it again is at ambient temperature, the fact that a pan expands during heating and becomes deformed during use is objectionable, because fluids often will not be uniformly distributed in the bottom of the pan.

When food is being heated in an oven, the parts of the pan against which the food bears prevents such parts from being heated at the same rate and to the same elevated temperature as other parts of the pan. Under these conditions adjacent parts of a pan often are heated to different elevated temperatures and the temperature difference of adjacent parts can be so great that the elastic limit will be passed when the pan expands during use. When this occurs a pan will not return to its original shape at ambient temperature and will be permanently deformed which is objectionable.

SUMMARY OF THE INVENTION

It is an object of the invention to provide open top multisided baking pans having outwardly flaring flat top flanges which are stiffened and reinforced at the corners of the pan. This is accomplished by providing a top flange which includes straight sections of uniform width and corners therebetween which are of greater width. The radius of curvature of the outer peripheral edge of each corner of the top flange is less than the radius of curvature of its inner peripheral edge. With this arrangement the center of the radius of curvature of the outer peripheral edge of the top flange at each corner thereof is located at a corner of the top flange bridging and connecting adjacent straight sections of the top flange.

Stated another way, in a baking pan embodying the invention each corner of an outward flaring top flange is stiffened and reinforced by a zone thereof which extends outward beyond an arc of a circle connecting the outer peripheral edges of adjacent straight sections of the top flange and having the same center of radius of curvature as that of the inner peripheral edge of the corner of the top flange. Also, the ends of adjacent straight sections of the bottom flange are disposed beneath the outward extending zone of each corner of the top flange to further stiffen and reinforce the top flange at each corner.

Further objects and advantages of the invention will become apparent as the following description proceeds, and the features of novelty which characterize the invention will be pointed out with particularity in the claims annexed to and forming a part of this specification.

BRIEF DESCRIPTION OF THE DRAWING

FIG. 1 is a fragmentary bottom perspective view of a baking pan embodying the invention;

FIG. 2 is a fragmentary top perspective view of the baking pan shown in FIG. 1;

FIG. 3 is a fragmentary bottom view of the baking pan shown in FIGS. 1 and 2; and

FIG. 4 is a sectional view taken at line 4-4 of FIG. 3.

DESCRIPTION OF THE PREFERRED EMBODIMENT

Referring to FIGS. 1 and 2, the invention is shown embodied in a pan 10 which is stamped from a rectangular sheet of metal. The multisided open top pan 10 includes a bottom 11 and opposing pairs of upstanding side walls 12 and 14 and a flat top flange 15 which flares outward at the open top of the pan.

The top flange 15 extends about the entire periphery of the pan 10 and includes straight sections 15a and corners 15b therebetween. A rim 16, which depends downward from the

outer peripheral edge of the top flange 15, extends lengthwise thereof about the straight sections 15a and corners 15b therebetween.

A bottom flange 17 extends inward toward the sidewalls 12 and 14 from the bottom of the rim 16 and terminates at regions removed from the sidewalls. The bottom flange 17 only includes straight sections 17a which extend inward from the bottom of the rim 16 at the straight sections 15a of the top flange 15. Hence, the straight sections 17a of the bottom flange 17 are separated from one another at the corners of the pan 10 at regions beneath the corners 15b of the top flange 15.

In accordance with this invention the width of the top flange 15 at the corners 15b is greater than the width *a* of the top flange at the straight sections 15a. With this construction the center A of the radius of curvature *b* of the rim 16 at each corner 15b of the top flange 15 is located on the top flange. Further, the radius of curvature *b* of the rim 16 at each corner 15b of the top flange 15 is less than the radius of curvature *c* of each corner at its inner peripheral edge. Stated another way, the radius of curvature *b* of the outer peripheral edge of the top flange 15 at each corner 15b is less than the radius of curvature *c* of the inner peripheral edge of the top flange at each corner.

25 In the pan 10 the upstanding sidewalls 12 and 14 slope outward from the vertical. As seen in FIG. 3, the round corner 18 formed between inclined sidewalls 12 and 14 has a small radius of curvature *-d* at the bottom 11 of the pan 10 and a larger radius of curvature *c* at the inner peripheral edge of the flange 15 at the corner 15b.

30 In pans of the kind being described, it has been the practice heretofore to provide a top flange in which the straight sections and corners thereof are of the same width. In pans of this type the outer peripheral edge of each corner of the top flange 35 connects the outer peripheral edges of adjacent straight sections thereof by an arc of a circle which is illustrated in FIG. 3 by a curved dotted line 19 having a radius of curvature *e*, the center B of which is the same as that of the radius of curvature *c* of the inner peripheral edge of the corner 15b of the top flange 15.

35 By providing the top flange 15 with the corners 15b, each of which has an outer peripheral edge whose radius of curvature *b* is less than the radius of curvature *c* of its inner peripheral edge, each corner 15b of the top flange 15 is stiffened and reinforced by a zone F which extends outward beyond the arc 19 of a circle connecting the outer peripheral edges of adjacent straight sections 15a of the top flange 15 and having the same center B of radius of curvature *e* as that *c* of the inner peripheral edge of the corner 15b of the top flange.

40 If the straight sections 15a and corners 15b of the top flange 15 were of the same width and the straight sections were connected at their outer peripheral edges by the curved dotted line 19, the ends of the bottom straight flange sections would terminate at the regions H which are located at about the 45 points where the corners of the top flanges would start. However, by providing the zone F at each corner 15b of the top flange 15, the ends of the adjacent straight sections 17a of the bottom flange 17 can be terminated at regions which are 50 disposed beneath each zone F to further stiffen and reinforce the top flange 15 at each corner 15b. With this arrangement the gap G between the inner corners 20 of each pair of adjacent straight sections 17a of the bottom flange 17, when extended as much as possible, is shorter than the radius of curvature *b* of the rim 16 at each corner 15b of the top flange 15.

55 In view of the foregoing, it will now be understood that the pan 10 of the invention can be formed from a rectangular sheet of metal having only small parts of the corners of the sheet cut to provide a top flange 15 in which the center of the 60 radius of curvature of the outer peripheral edge of each corner 15b is located on the top flange 15.

65 I claim:

1. An open top multisided baking pan having: a bottom and upstanding sidewalls and a top flat flange which flares outward at the open top thereof,

- b. said top flange including straight sections of uniform width and corners therebetween,
  - c. a rim which extends about the straight sections and corners of said top flange and depends vertically downward from the outer peripheral edge thereof,
  - d. a bottom flange having straight sections which extend inward toward said sidewalls from the bottom of said rim at the straight sections of said top flange and terminate at regions removed from said sidewalls, the straight sections of said bottom flange being separated from one another at the corners of the pan at regions beneath the corners of said top flange,
  - e. the center of the radius of curvature of said rim at the corners of said top flange being located on said top flange,
  - f. the width of said top flange at the corners being greater than at the straight sections,
  - g. the radius of curvature of said rim at each corner of said top flange being less than the radius of curvature of each corner at its inner peripheral edge, and
  - h. the gap between the inner corners of each pair of adjacent straight sections of said bottom flange being shorter than the radius of curvature of said rim at each corner of said top flange.
2. An open top multisided baking pan having:
- a. a bottom and upstanding sidewalls and a top flat flange which flares outward at the open top thereof,
  - b. said top flange including straight sections of uniform width and corners therebetween,
  - c. a rim which depends vertically downward from the outer peripheral edge of said top flange,
  - d. a bottom flange having straight sections which extend inward toward said sidewalls from the bottom of said rim at the straight sections of said top flange, the straight sections of said bottom flange being separated from one another at the corners of the pan at regions beneath the corners of said top flange,

5

- 5
- e. the center of the radius of curvature of the outer peripheral edge of said top flange at each corner thereof being located on said top flange,
  - f. the center of the radius of curvature of the outer peripheral edge of said top flange at each corner thereof being located at a corner of said top flange bridging and connecting adjacent straight sections of said top flange, and
  - g. the end portions of each pair of adjacent straight sections of said bottom flange terminating at a region beneath a corner of said top flange which is between the outer peripheral edge of said top flange at the corner and the center of the radius of curvature of the outer peripheral edge of the corner.
3. An open top multisided baking pan having:
- a. a bottom and upstanding sidewalls and a top flat flange which flares outward at the open top thereof,
  - b. said top flange including straight sections of uniform width and corners therebetween,
  - c. a rim which depends vertically downward from the outer peripheral edge of said top flange,
  - d. a bottom flange having straight sections which extend inward toward said sidewalls from the bottom of said rim at the straight sections of said top flange, the straight sections of said bottom flange being separated from one another at the corners of the pan at regions beneath the corners of said top flange, and
  - e. each corner of said top flange being stiffened and reinforced by a zone thereof which extends outward beyond an arc of a circle connecting the outer peripheral edges of adjacent straight sections of said top flange, and
  - f. the ends of adjacent straight sections of said bottom flange being disposed beneath said outward extending zone of each corner of said top flange to further stiffen and reinforce said top flange at each corner.
